[57] **CLAIM**

The ornamental design for a building for dispensing ice
cream, substantially as shown.

DESCRIPTION

FIG. 1 is a front perspective view of building for dis-
pensing ice cream showing my new design;

FIG. 2 is a front elevational view thereof;

FIG. 3 is a side elevational view looking from the left

side of FIG. 1; and

FIG. 4 is a rear elevational view.
